(57) **CLAIM**

We claim the ornamental design for a stand for monitor, as shown and described.

DESCRIPTION

FIG. 1 is a front perspective view of a stand for monitor showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another rear perspective view thereof, shown in an environment of use.

FIG. 10 is an enlarged view of the encircled portion shown in FIG. 5; and,

FIG. 11 is an enlarged view of the encircled portion shown in FIG. 9.

The evenly-spaced broken lines illustrating the monitor and printer in FIGS. 1-11 are environment, while the remaining evenly-spaced broken lines in FIGS. 1-11 illustrate portions of the stand for monitor that form no part of the claimed design. The dash-dot-dash lines shown in FIGS. 1, 4, 5 and 8-10 illustrate boundaries of the claimed design that form no part thereof. The dot-dot-dash lines encircling portions of the claimed design that are illustrated in enlargements form no part thereof.
